UNITED STATES PATENT OFFICE

VINCENT BENDIX, OF CHICAGO, ILLINOIS

ENGINE STARTER

Application filed June 18, 1917. Serial No. 175,431.

My invention pertains to an engine starter and relates more particularly to the so-called transmission or drive for transmitting the power of the starting motor, such as an electric motor, to a rotatable member or wheel of the engine to be started, such as the fly wheel.

The object of my invention is to produce a simple and efficient form of drive or transmission, as well as such a drive in combination with a novel form of engine member or wheel in which the gear ring has a yielding relative movement with respect to the wheel proper.

In the drawing, Fig. 1, is an elevation of a transmission or drive embodying my invention and showing a portion of the engine fly wheel with a slidable ring, and Fig. 2 a section on the line 2-2 of Fig. 1.

Describing my invention, it will first be understood that the driving shaft which is here the screw shaft, may be driven directly or indirectly by the starting motor. In the present instance this driving shaft is shown as direct driven by the starting motor, illustrated as A, being here the extended portion of the armature shaft. The inner portion of this shaft is preferably made plain and its outer portion provided with screw threads 2, while its extreme outer end is screw-threaded at 3 to receive the stop nut 4, which by preference is also secured by the pin 5.

The driving member which is adapted to engage the member of the engine to be started is shown as a pinion 6, which has a hollow portion or cylinder 6^a at one end. This pinion has a central, smooth bore adapted to fit upon the plain cylindrical portion of the shaft 1 and such pinion has a longitudinal movement on the screw shaft as well as a rotary movement therewith.

Within the cylindrical portion of the pinion is located a screw member in the form of a nut 7 screw-threaded upon the threaded portion of the shaft and capable of longitudinal movement thereof and rotary movement therewith. This nut is operatively connected in suitable manner with the pinion so as to directly and positively drive the

latter, such driving connection, as herein shown, comprising a key 8 extending in a line parallel with the axis of the pinion and screw member, with the result that the latter is capable of a longitudinal movement with respect to the pinion. A compression spring 9 is interposed between the pinion and screw member, the same being a coiled spring abutting at one end against the bottom of the cylindrical portion of the pinion 60 and at the other end at the bottom of an annular recess 7^a in the screw member. Such screw member is retained within the pinion in suitable manner as by means of a marginal flange 10 removably secured to the 65 outer end of the pinion.

Describing the operation of the drive and starting with the parts in their relative position as shown, when the electric motor is started and the shaft 1 is rotated, the 70 screw member will be moved inwardly toward the motor and will carry or move the pinion bodily in that direction, although by suitable reversals including reversing the direction of the threads such pinion would 75 move outwardly for meshing. When the pinion has fully meshed with the teeth 12^a of the gear ring 12 and has come into contact with the stop shoulder 11 of the shaft, such pinion will be rotated by the shaft 80 through the medium of the screw member.

In the event that the pinion teeth should abut the gear teeth end to end, the pinion will be momentarily stopped and the screw member will continue moving inwardly toward the motor against the tension of the spring 9. Thereupon the pinion will be turned slightly with the result that the teeth will be brought into register and meshing will take place. After the engine has started 85 on its own power the pinion will be automatically demeshed, whereupon the parts will return to their normal position shown.

My drive is designed to operate in connection with any kind of yielding driving 90 means located between it and the engine or forming part of the engine, such as a fly wheel provided with a yielding gear or gear ring, thereby providing a yielding driving connection between the starting motor and

the engine to be started. In the present instance, the engine member is the fly wheel, and the same is made in two parts, that is, the gear ring 12 and the wheel proper marked 13. The gear ring is mounted to slide or slip peripherally on the wheel and is held to a normal position with a yielding pressure, as by means of the springs 14. These springs are arranged in pairs and are coil springs with their ends anchored respectively to the ring and wheel in such manner that they tend to resist movement of the ring in either direction, with the result that they act as a yielding driving connection and also absorb the shock and jar incident to back firing. The springs of each pair are anchored at their inner ends to a common anchoring point or stud 15 secured to a wheel and at their outer ends to separate anchoring points or studs 16 secured to the ring. By preference the stud 16 projects farther away from the face of the wheel than the stud 15 so that the springs have the additional function of holding the gear ring in place on the wheel by holding it into contact with the annular shoulder 13^a thereof.

There is thus provided for the drive described a yielding driving connection between the driving member and the engine member.

I claim:

1. The combination of a rotatable screw shaft, a driving member, a screw member screw-threaded on the shaft and connected with the driving member for rotary movement therewith and longitudinal movement relative thereto, and a yielding means cooperating with the two members for normally holding them extended.

2. The combination of a rotatable screw shaft, a driving member, a screw member screw-threaded on the shaft and connected with the driving member for longitudinal movement relative thereto, and a spring operating with the two members for normally holding them extended.

3. The combination of a rotatable screw shaft, a driving member, a screw member screw-threaded on the shaft and connected with the driving member for rotary movement therewith and longitudinal movement relative thereto, yielding means cooperating with the two members for normally holding them extended, and means for limiting such extension.

4. The combination of a rotatable screw shaft, a driving member, a spring, a slidable drum, a screw member having direct rotative engagement with said drum and screw-threaded on the shaft and operatively connected with the driving member through said spring and slidable drum for longitudinal movement and adapted and arranged to transmit driving torque to said driving

member after the longitudinal movement has ceased.

5. In a starter for gas engines and the like, a combined shifting and starting member including; a drum, a driving gear supporting one end of said drum, a rigid member slidably connecting the other end of the drum to a motor driven element, and a spring positioned between said gear and rigid member.

6. The combination of a rotatable driving shaft, a driving member, and a control member mounted on the shaft for longitudinal movement thereon and rotary movement therewith, said members being constantly connected together for rotary movement in unison and for longitudinal movement with respect to each other.

7. The combination of a rotatable driving shaft, a driving member, and a control member mounted on the shaft for longitudinal movement thereon and rotary movement therewith, said members being constantly connected together for rotary movement in unison and for longitudinal movement with respect to each other, and yielding means between such members for moving the driving member longitudinally.

8. The combination of a rotatable screw shaft, a driving member having a hollow portion, and a screw member therein mounted on the screw shaft and constantly positively connected with the driving member for rotary movement.

9. The combination of a rotatable screw shaft, a driving member having a hollow portion, and a screw member therein mounted on the screw shaft and constantly positively connected with the driving member and capable of longitudinal movement relative thereto.

10. The combination of a rotatable screw shaft, a driving member having a hollow portion extending therefrom, and a screw member therein mounted on the screw shaft and capable of longitudinal movement relative thereto, and a yielding means for extending the two members.

11. The combination of a rotatable screw shaft, a pinion mounted to slide on the shaft and having a hollow portion, and a screw member located in such hollow portion and screw-threaded on the shaft, and a spring cooperating with the screw member and pinion.

12. The combination of a rotatable screw shaft, a pinion mounted to slide on the shaft and having a hollow portion, and a screw member located in such hollow portion and screw-threaded on the shaft, said member being operatively connected with the pinion for rotary movement therewith and for longitudinal movement relative thereto, and means for limiting the longitudinal move-

ment of the screw member in one direction.

13. The combination of a rotatable screw shaft, a pinion mounted to slide on the shaft and having a hollow portion, and a screw member located in such hollow portion and screw-threaded on the shaft, said member being operatively connected with the pinion for rotary movement therewith and for longitudinal movement relative thereto, said pinion having a flange to limit the longitudinal movement of such member in one direction.

14. An engine starter drive including a rotatable shaft, a driving member, and a control member mounted on the shaft for longitudinal movement thereon and rotary movement therewith, said members being operatively connected together for positive rotary movement and yieldingly for longitudinal movement one with respect to the other.

15. An engine starter drive including a rotatable screw shaft, a control member threaded on the shaft for longitudinal movement thereof and for rotary movement therewith, a driving member operatively connected with the control member for positive rotation therewith and adapted to be shifted longitudinally by such control member into operative engagement with a part of the engine to be started, said control member having a yielding longitudinal movement toward the driving member after the latter has been shifted into operative engagement with the engine part.

16. An engine starter drive including a rotatable shaft, a driving member, a control member mounted on the shaft for longitudinal movement thereon and rotary movement therewith, and a cylinder operatively connected with said two members for their positive rotary movement and for yielding longitudinal movement, one with respect to the other.

17. An engine starter drive including a rotatable shaft, a driving member, a control member mounted on the shaft for longitudinal movement thereon and rotary movement therewith, and a cylinder operatively connecting said two members together, said driving member being connected with the cylinder for both rotary and longitudinal movements together, and the control member being connected with such cylinder for rotary movement together but having a longitudinal movement with respect to the cylinder.

18. A drive for engine starters comprising a rotatable shaft, a control member mounted thereon for longitudinal movement thereof and rotary movement therewith, a driving member adapted to engage an engine member and controlled in its movements by the control member, and means for so controlling the movements of said driving member connecting between the control and

driving members and including a positive rotary connection between them and a compression spring interposed between them.

19. A drive for engine starters comprising a rotatable shaft, a nut mounted thereon for longitudinal movement thereof and rotary movement therewith, a pinion adapted to engage an engine member and controlled in its movement by the nut, said pinion being mounted to slide longitudinally on the nut, and a spring arranged between the nut and pinion and adapted to be compressed by the continued longitudinal movement of the nut whenever the pinion is stopped in its similar movement by abutting the engine member.

20. An engine starter drive including a rotatable driving shaft, a control member mounted for longitudinal movement thereof and rotary movement therewith, a driving member mounted for longitudinal movement for engagement with a member of the engine to be started and for rotary movement to rotate such engine member and controlled and actuated in such movements by the control member, and means for stopping said longitudinal movement of the driving member, said control member being capable of a longitudinal movement independent of the driving member.

21. An engine starter drive including a rotatable driving shaft, a control member mounted thereon for longitudinal movement thereof and rotary movement therewith, a driving member mounted for longitudinal movement for engagement with a member of the engine to be started and for rotary movement to rotate such engine member and controlled and actuated in such movements by the control member, and stop means located on the shaft for stopping said longitudinal movement of the driving member, said control member being capable of a longitudinal movement independent of the movement of the driving member.

22. An engine starter drive including a rotatable driving shaft, a control member mounted thereon for longitudinal movement thereof and rotary movement therewith, a driving member mounted for longitudinal movement for engagement with a member of the engine to be started and for rotary movement to rotate such engine member and controlled and actuated in such movements by the control member, said shaft having a stop shoulder for stopping said longitudinal movement of the driving member, said control member being capable of a longitudinal movement independent of the movement of the driving member.

23. An engine starter drive including a rotatable driving shaft, a control member mounted thereon for longitudinal movement thereof and rotary movement therewith, a driving member mounted for longitudinal movement for engagement with a member of

- the engine to be started and for rotary movement to rotate such engine member and controlled and actuated in such movements by the control member, means for stopping said longitudinal movement of the driving member, said control member having a longitudinal movement independent of the driving member, whereby such control member may move longitudinally on the shaft without disturbing the position of the driving member after its engagement with the engine member, and yielding means between the driving member and the control member for resisting such movement of the control member. 70
24. An engine starter drive including a rotatable screw shaft, a control member screw-threaded thereon for longitudinal movement thereof and rotary movement therewith, a driving member controlled by said control member and mounted for longitudinal movement for engagement with a member of the engine to be started, and for rotary movement to rotate such engine member, and means for stopping the longitudinal movement of the driving member without stopping the longitudinal movement of the control member, said control member having a longitudinal movement independent of the movement of the driving member. 75
25. An engine starter drive including a rotatable screw shaft, a control member screw-threaded thereon for longitudinal movement thereof and rotary movement therewith, a pinion interlocked with the control member and having imparted to it therefrom corresponding longitudinal and rotary movements, said control member having a longitudinal movement independent of the movement of the pinion, and means for stopping the longitudinal movement of the pinion when engaged with a member of the engine to be started. 80
26. An engine starter drive including a rotatable member, a control member mounted thereon for longitudinal movement thereof and rotary movement therewith, a driving member mounted for longitudinal movement for engagement with a member of the engine to be started and for rotary movement to rotate such engine member and controlled and actuated in such movements by the control member, said control member and rotatable member having cooperating screw threads and the driving member having a central bore adapted to slide on one of the other members, and means for stopping said longitudinal movement of the driving member, said control member having a longitudinal movement independent of the movement of the driving member. 85
27. In apparatus of the character described, in combination, a motor-driven shaft having a threaded part, a driving gear on said shaft adapted to cooperate with a driven gear, a nut on said threaded part, a coil spring interposed between said nut and said driving gear, and means to limit said driving gear against further translation when in mesh with said driven gear, whereby said nut may continue its translatory movement along said shaft compressing said spring, when said gears are in mesh. 90
28. In a starter for internal combustion engines and the like, in combination, a motor driven shaft having a threaded portion and a smooth portion, a nut on said threaded portion, a pinion on said smooth portion, a coil spring interposed between said nut and said pinion, a stop coacting with said pinion for preventing further translation thereof when in mesh with said gear, and means for compelling said pinion to rotate with said nut. 95
29. In a starter for internal combustion engines and the like, in combination, a motor driven shaft having a threaded portion, and a smooth portion, a pinion on said smooth portion, adapted to mesh with an engine gear, a nut cooperating with said threaded portion, a coil spring interposed between said nut and said pinion, a stop coacting with said pinion for preventing further translation thereof when in mesh with said gear, and a barrel enclosing said spring, and connecting said pinion and said nut, said barrel being rigidly connected with one of said latter members, and limited against rotation with respect to the other. 100
30. An apparatus of the character described, in combination, a motor driven shaft, a pinion on said shaft, adapted to mesh with a member of the engine to be started, a nut threaded on said shaft, adapted upon rotation of said shaft to urge said pinion into mesh with said engine member, a stop for limiting the translation of said pinion when in mesh, means for tightening said nut on said shaft after said pinion is stopped, and a barrel rigid with said pinion and connected to said nut to permit substantial translation thereof, after meshing, and to prevent relative rotation. 105
31. In apparatus of the character described, in combination a normally disconnected transmission adapted for connection between a motor and an engine, said transmission including a shifting member, and an engine-engaging member, a stop adapted to engage the latter member, for arresting further shifting of said transmission when in operative position, and means interposed between said shifting member and said engine engaging member, for gradually increasing the torque imparted to said engine-engaging member after shifting of the latter is arrested. 115
32. As an article of manufacture, an automatic transmission member for engine starters, for mounting as a unit on a motor-driven 120
- 125
- 130

shaft, said transmission comprising a pinion, a nut, an interposed spring, and a barrel surrounding said spring and having such connections with said pinion and said nut as to prevent their relative rotation, and to permit some relative translation.

33. In an engine starter, in combination with a driving shaft, a transmission member including shifting means operatively connected with said shaft, a driving member and a member to transmit torque to said driving member when the latter is in operative relation, said shifting means, driving member and member to transmit torque having mutually sustaining inter-engagement whereby said transmission member may be placed on said shaft as a unit, and a stop on said shaft to engage said driving member when in driving position.

34. In a starter for gas engines and the like, in combination, an engine-driven member, a motor, a driving member connected to said motor, adapted to cooperate with said driven member, means whereby the starting of the engine automatically brings about disengagement between said driving and said driven members, and means to prevent movement of said driving member in the direction of disengagement during cranking action.

35. A drive for engine starters comprising a rotatable screw shaft, a driving member mounted for longitudinal and rotary movement with relation to the shaft and rotary movement therewith, a screw member mounted for longitudinal movement on said shaft and controlling the relative movements of the driving member, and a driving connection established between the said screw shaft and driving member after the driving member has moved to its limit in one direction by final longitudinal movement of the screw member.

36. A drive for engine starters comprising a rotatable screw shaft, a driving member mounted for longitudinal and rotary movement with relation to the shaft and rotary movement therewith, a screw member mounted on said shaft and controlling the relative movements of the driving member, a driving connection established between the said screw shaft and driving member after the driving member has moved to its limit in one direction by final longitudinal movement of the screw member and a spring for cushioning the establishment of the driving connection.

37. The combination of a rotatable driving shaft, a driving member, a control member mounted on the shaft for longitudinal movement therewith and adapted to control the similar movements of the driving member, a yielding means which by reason of its resistance cooperates with the control member for transmitting the initial torque, a member driven

by said driving member and a second yielding means cooperating with said driven member for taking extreme torque.

38. The combination of a screw-threaded shaft, a pinion mounted thereon, a control member threaded on the shaft for longitudinal movement thereon and rotary movement therewith and adapted to control the similar movements of the pinion, a spring which by reason of its resistance cooperates with the pinion and control member for transmitting the initial torque, a member driven by said driving member and a spring means cooperating with said driven member for taking extreme torque.

39. The combination of a rotatable driving shaft, a driving member, a control member mounted on the shaft for longitudinal movement thereon and rotary movement therewith and adapted to control the similar movements of the driving member, a yielding means which by reason of its resistance cooperates with the driving and control members for permitting yielding longitudinal movement of the driving member with respect to the control member and for taking the initial torque, a member driven by said driving member, and a second yielding means cooperating with said driven member and complementing the first yielding means with respect to transmission of torque.

40. The combination of a rotatable shaft, a driving member mounted thereon for longitudinal movement thereof and rotary movement therewith, and having an integral hollow portion and forming an annular space around the shaft, and means located within said space and forming the operating connection between said shaft and driving member for moving said driving member longitudinally and for rotating it.

41. The combination of a rotatable shaft, a driving member mounted thereon for longitudinal movement thereof and rotary movement therewith and having an integral hollow portion and forming an annular space around the shaft, and screw action means located within said space and forming the operating connections between said shaft and driving member for moving said driving member longitudinally and for rotating it.

42. The combination of a rotatable shaft, a driving member mounted thereon for longitudinal movement thereof and rotary movement therewith and having an integral hollow portion and forming an annular space around the shaft, screw action means located within said space and forming the operating connections between said shaft and driving member for rotating the latter, said means and driving member having a relative longitudinal movement, and yielding means tending to resist such relative movement.

43. The combination of a rotatable shaft, a driving member mounted thereon, a con-

trol member operatively connected with said shaft and cooperating with the driving member for determining its position longitudinally and for unyieldingly rotating it,
5 said members having a relative longitudinal movement, and yielding means tending to resist such relative movement.

44. The combination of a rotatable shaft, a driving member having a hollow portion,
10 a screw member therein mounted on the shaft and operatively connected therewith and with such hollow portion, said hollow portion and the screw member having relative longitudinal movement, and yielding means tending to resist such relative movement.

45. In apparatus of the class described, in combination, an engine-driven gear, a driving gear adapted to cooperate therewith, a spring operatively associated with said driving gear, means normally separated from said driving gear by said spring and movable to compress said spring and engage said driving gear for transmitting a part of the driving torque by reason of the resistance of
20 said spring and the balance by reason of the engagement of said means with the driving gear, and a motor-driven member for actuating said means.
